UNITED STATES PATENT OFFICE.

FRANK D. LEIPOLD, OF CLEARFIELD, PENNSYLVANIA.

AMALGAM MIXER.

1,421,016.

Specification of Letters Patent. Patented June 27, 1922.

Application filed January 12, 1922. Serial No. 528,713.

To all whom it may concern:

Be it known that I, FRANK D. LEIPOLD, a citizen of the United States, residing at Clearfield, in the county of Clearfield and 5 State of Pennsylvania, have invented certain new and useful Improvements in Amalgam Mixers, of which the following is a specification.

This invention relates to certain new and 10 useful improvements in amalgam mixers, and the primary object of the invention is to provide a device of this type which can be easily and quickly attached to a dental engine so as to be operated thereby and which 15 is formed so as to be held in and steadied by the hand of the dentist during the operation of mixing.

A further object of the invention is to 20 provide a device of this kind which is equipped with a sleeve or chuck that can be easily and quickly applied to the flexible driving shaft of the engine and removed therefrom so as to thus enable the mixing to be effected expeditiously.

25 The invention still further aims to provide a mixer which is positive and certain in action and which is composed of a minimum of parts of simple and economical constructions that are compactly related so as to 30 provide convenient storage when out of use.

The invention also aims to provide a glass 35 receptacle and means for sealing the inlet thereof during the mixing operation and to also provide a holder for the receptacle which will positively and firmly support the latter and still permit of ready removal thereof.

Other and further objects will be later 40 set forth and manifested in the course of the following description.

In the drawings:—

Figure 1, is a top plan view of the preferred form of the invention;

Figure 2, is a side elevation thereof;

45 Figure 3, is a section on line 3—3 of Figure 1;

Figure 4, is a section on line 4—4 of Figure 1, and

50 Figure 5, is a side elevation of a modified form of the invention.

In proceeding in accordance with the present invention a sleeve or chuck 1 is employed and which is preferably knurled or suitably roughened to afford a firm finger 55 grip. The chuck has its inner end formed with slotted parts 2 and 3 for engagement

with dental engines of varying types, some of which types fit part 2 and others part 3, the chuck being thus adapted for use with either type. A driving shaft 4 is suitably 60 mounted in the chuck and is received by the usual chuck of the flexible shaft of the dental engine so as to be driven by the latter.

An arm 5 is rigidly secured at one end to the chuck 1 and has an upwardly 65 extending thumb piece 6 on its opposite outer end. The shaft extends through the arm 5 and has a crank 7 rigidly secured thereto. Arranged in front of the thumb piece 6 is an upwardly extending post 8 to which a link 9 is pivoted by means of a screw 10. The link 9 is slotted at 11 at its outer end and slidably receives the crank pin of the crank 7, the latter having a screw 12 secured thereto so as to prevent movement of the link from the crank pin.

The outer end of the link is formed with lateral arms affording a suitable support 13 for a receptacle holder 14, the latter having ends 15 and 16, the ends being provided with circular rims 17 and 18 respectively. A suitable sealing element such as cork, or rubber 19, or the like is frictionally or otherwise secured in the rim 17, while a follower 80 disk 20 tensioned by a coil spring 21 is 85 slidable in the rim 18. The holder 14 is open or cutaway along its sides and top, to enable a preferably glass receptacle 22 to be placed in and removed from the holder 90 with its open end abutting and sealed by the element 19, while its closed end is engaged by the follower disk 20, which latter not only holds the receptacle in the holder but also exerts constant tension thereon to 95 maintain the open end thereof in sealing engagement with the sealing element 19. By merely grasping the receptacle in the fingers, same may be moved against the tension of the follower disk to bring the open 100 end free of engagement with the rim 17 whereupon the receptacle may be disengaged from the holder. In order to place the receptacle in the holder, the closed end is impinged against the disk 20 and moved to 105 force the disk inwardly against its spring until the open end of the receptacle is in register with the rim 17, whereupon release of the receptacle allows the tensioned disk to move the receptacle to the position of 110 Figure 3.

In operation, the sleeve or chuck 1 is first

moved or slid into engagement with the usual chuck of the dental engine flexible shaft, causing automatic coupling of the driving shaft 4. The thumb of the hand 5 is engaged with grip 6 and the fingers engaged with the chuck to thus hold and steady the device in the hand of the operator. Power being applied, shaft 4 is rotated and therewith crank 7 which effects 10 oscillation of the holder 14 and therewith the amalgam. The receptacle is made of sufficient length so that the amalgam will be impacted with quite a little force both against the closed end of the receptacle and 15 against the seal 19 to thus efficiently unite the mercury and alloy. It will further be seen that the receptacle has oscillatory movement in a curved line thus simulating shaking of the amalgam in a bottle held in the 20 hand of the dentist. The receptacle being formed of glass the amalgam is visible to allow the dentist to observe the mixing and to determine when same is completed, without removing the receptacle from the holder. 25

In Figure 5, a modified form is illustrated, and wherein an arm 30 is employed secured to chuck 1, the latter being identical with the form in Figures 1 to 4. The arm has a depending thumb grip 31 and is slotted at 30 32 to slidably receive a pivotal member 33, the latter being secured to a holder 34 which latter also is identical with the form of the invention illustrated in Figures 1 to 4. A crank 35 is secured to the shaft of the 35 chuck and is pivoted by member 37 to the holder.

In both forms of the invention, it will be observed that the receptacle is supported not only at each end, and in a horizontal 10 position, but in addition the lowermost part of the receptacle is supported throughout its length, as Figure 3 clearly illustrates.

What is claimed is:

1. In an amalgam mixer, a chuck having a driving shaft, the chuck and shaft being formed for coupling to the flexible shaft of a dental engine, an arm on the shaft having a thumb member to allow the device to be held by engaging the thumb with said member and the fingers with said chuck, a holder, an amalgam receptacle carried by the holder, means to pivot the holder to the arm, and means carried by the shaft to oscillate the holder.
- 5 2. In an amalgam mixer, a chuck formed for operative connection with the driving shaft of a dental engine and having driving means associated therewith, a holder, a receptacle removably carried by the holder, a member carried by the chuck and having a hand engaging part to allow the device to be held by engaging the hand with said part and with the chuck, and means actuated by said driving means for effecting agitation of the holder.

3. In an amalgam mixer, a chuck formed for operative connection with the driving shaft of a dental engine, a supporting member carried by the chuck, a holder having a bottom and open sides and top and having 70 ends formed with rims which extend inwardly of the holder, a spring pressed follower in one of the holder ends, a sealing element in the other holder end, a receptacle having a closed and an open end the latter 75 engageable with the sealing element and the closed end being engaged by the follower, and means to agitate the holder.

4. In an amalgam mixer, a holder having an open side, and ends, a sealing element 80 associated with one end, a spring pressed follower associated with the other end, a receptacle movable through the open side and having a closed end engageable with the follower and an open end engaged with the 85 sealing element, and agitating means for the holder.

5. In an amalgam mixer, a hand engaging member, a supporting member carried by the hand engaging member and having a 90 finger engaging member so as to allow the device to be held by engaging the hand with each of said members, a holder on the supporting member, a receptacle in the holder, and means to agitate the holder. 95

6. In an amalgam mixer, a hand engaging member, a supporting member carried by the hand engaging member and having a finger engaging member so as to allow the device to be held by engaging the hand with 100 each of said members, a holder on the supporting member, a receptacle in the holder, and means carried by the hand engaging member and connected to the holder for agitating the latter. 105

7. In an amalgam mixer, a sleeve formed for connection with the driving shaft of a dental engine and having driving means therein, an arm on the sleeve having a thumb engaging member, a crank carried by said 110 driving means, a link pivoted to the arm and having a slot receiving one end of the crank, a holder secured to the link, and a receptacle carried by the holder.

8. In an amalgam mixer, a hand engaging member, an arm carried by said member and having an outwardly extending thumb grip, a holder supported by the arm, a receptacle carried by the holder, and means to agitate the holder. 115

9. In an amalgam mixer, a hand engaging member, driving means therein, an arm on the member having a thumb-engaging part a receptacle holder on the arm, and means actuated by the driving means to implement an agitating movement to the holder. 125

10. In an amalgam mixer, a hollow device formed for holding in the hand, driving means disposed within said device, a receptacle holder carried by the device, and 130

means actuated by the driving means to impart an agitating movement to the holder.

11. In an amalgam mixer, a holder having a sealing means and a spring pressed follower, a receptacle closed at one end and engaged by the follower and having its opposite end open and engaged with the sealing means, said holder having a part on which a side of the receptacle rests and being formed to allow the receptacle to be moved outwardly from said part and removed from the holder, and agitating means for the holder.

12. In an amalgam mixer, a holder having sealing means and a spring pressed follower located in opposed and spaced relation to the sealing means, a receptacle having one end engaged by the follower and having its opposite end open and engaged 20 with the sealing means to be sealed thereby,

said holder being formed to allow the receptacle to be removed by being moved outwardly therefrom and from between the follower and sealing means, and means to agitate the holder.

25

13. In an amalgam mixer, a hollow handle, driving means therein, a member supported by the handle, a receptacle carrier movably connected to the member and means actuated by the driving means to effect agi- 30 tation of the carrier.

14. In an amalgam mixer, a hollow handle, driving means therein, a member supported by the handle, a receptacle carrier movably connected to the member and a 35 crank on the driving means pivoted to the carrier to effect agitation of the latter.

In testimony whereof I affix my signature.

FRANK D. LEIPOLD.
